SEWING HEAD

Frederick N. Ross and Horace L. Johnson, Detroit, Mich., assignors, by mesne assignments, to Briggs Manufacturing Company, Detroit, Mich., a corporation of Michigan

Application October 17, 1929, Serial No. 400,317

27 Claims.

(Cl. 112—2)

This invention relates to a method and apparatus for sewing seat cushions and the like and more particularly to improvements therein tending to simplify, render more efficient and improve the same generally.

Heretofore, in the manufacture of what is known in the art as tubular upholstery, to which this invention particularly pertains, it has generally been customary, in automatic methods of manufacture, to unite the finish and lining fabrics by transverse stitching extending through nested seam ridges in the fabrics. In other methods of manufacture not involving automatic production, it has been customary to separately sew the seams defining the tubular portions of the upholstery, the trimming material or finish fabric being turned back at predetermined spaced intervals to form folds or seam ridges which were then united by stitching to the lining fabric.

In the upholstery produced with the heretofore known automatic method of manufacture serious objections have arisen owing to the fact that any stretching of the backing or lining fabric in the application of the upholstery to the cushion frame was exerted directly on the stitching uniting the finish and lining fabrics, with the result that the stitching frequently gave way under this continuous strain with resulting disorganization and damage to the upholstery.

While with the heretofore manually executed methods of upholstery manufacture such difficulties have not been experienced with the finished product, such manual methods of manufacture have become obsolete and impractical owing to the necessity of quantity production in articles of this nature.

It is therefore one of the important objects of this invention to provide a method of manufacturing cushions and the like wherein the finish fabric may be stitched or secured to the backing or lining fabric in such a manner that when the cushion is completed the lining fabric may be stretched taut without imposing any strain on the stitching.

Another object of this invention is to provide means for automatically constructing upholstery having these desirable characteristics.

More particularly it is the object of the present invention to provide a method and means for automatically manufacturing a multi-plait or multi-tube upholstery having the characteristics and advantages of the prior art hand-made upholstery.

In carrying out the present invention the fin-

ish fabric is gathered to provide a plurality of spaced seam ridges and the lining fabric or backing is arranged in superposed relation with respect to these seam ridges and with a portion of this lining fabric adjacent and parallel to the seam ridges at one side thereof. The finish and lining fabrics are then united at the seam ridges to form a plurality of plaits or tubes, the stitching extending through the portions of the lining fabric parallel and adjacent to the seam ridges and through the seam ridges into the tubes where the stitch is completed. When completed the seams are invisible on the face of the completed article, and in the subsequent application of the upholstery to the seat the lining fabric or backing may be stretched taut without imposing any strain to the stitching.

The present invention also has as one of its objects to provide a compact, simple, efficient and commercially practical sewing mechanism for industrial purposes whereby the heretofore mentioned objects and advantages of the present invention may be carried into execution.

The invention also contemplates a novel combination, construction and arrangement of parts, all of which will be made more apparent as this description proceeds, especially when considered in connection with the accompanying drawings wherein

Figure 1 is a vertical sectional elevational view of a sewing head;

Figure 2 is an enlarged fragmentary vertical sectional view through the cloth-forming mechanism at the point where the sewing takes place;

Figure 2a is a detail plan view of the needle guard.

Figure 3 is a fragmentary perspective view of the sewing head in one position of the parts;

Figure 4 is a similar view with the parts in another position;

Figure 5 is a fragmentary horizontal sectional view taken substantially on the plane indicated by line 5—5 in Figure 1;

Figure 6 is a fragmentary vertical sectional elevational view taken substantially on the plane indicated by line 6—6 in Figure 7;

Figure 7 is a fragmentary vertical sectional view taken substantially on the plane indicated by line 7—7 in Figure 6.

Figure 8 is a fragmentary side elevational view of one-half of the sewing head with the parts in one position;

Figure 9 is a similar view with the parts in another position;

Figure 10 is a fragmentary side elevational view

- of the sewing head showing the needle retracted; Figure 11 is a similar view showing the needle at the end of its forward thrust; Figures 12 to 21 inclusive diagrammatically illustrate the sewing operation; Figure 22 is an enlarged view showing the double chain lock stitch created; Figure 23 is a fragmentary view of the reverse side of the stitching; Figure 24 is a fragmentary vertical sectional elevational view of the cloth-forming mechanism adjacent the sewing zone; Figure 25 is a semi-diagrammatic view showing the manner in which the finish and lining fabrics are arranged during the sewing operation; Figure 26 is a similar view of the completed upholstery with the lining fabric stretched taut; Figure 27 is a semi-diagrammatic view showing the rocking movement of the needle arm and needle; and Figure 28 is a diagrammatic view showing the path of the needle point during the thrusting and retracting movements of the needle. Figure 29 is a diagrammatic view illustrating the feeding and the assembly of the materials. Referring now particularly to the drawings wherein like reference characters indicate like parts, and with particular reference to Figures 25 and 26, the general problem involved herein will be explained. In Figures 25 and 26 the finish or top fabric of the cushion or upholstery is indicated by the reference character F and the bottom or lining fabric is indicated by the reference character L. It is the purpose of this invention to provide a method and means of automatically uniting the finish and lining fabrics to provide a plurality of plaits or tubes with the stitching extending from the outside of the lining fabric into the interior of the tubes where the stitching is completed. In accordance with this invention the finish fabric is gathered to provide a plurality of spaced parallel seam ridges S and the lining fabric is arranged in superposed relation over the finish fabric with portions L' thereof adjacent to and parallel with the seam ridges S at one side thereof. The lining fabric is spaced from the seam ridges at the other side thereof to produce spaces X, providing clearance to enable the completion of the loop of the stitch within the completed tube T. The finish and lining fabrics are united by transverse stitching Y extending from the outside through the portions L' of the lining L and through the seam ridges S of the finish fabric F, the needles extending into the spaces X where the chain or loop of the stitches is completed. When the upholstery is subsequently applied to the seat the lining fabric L is stretched taut, but, as will be noted from Figure 26, no strain whatsoever will be imparted to the stitching Y. Moreover, the stitching is substantially invisible on the face of the completed upholstery. In this respect the finished upholstery is substantially the same as that constructed by the heretofore known manual methods of manufacture wherein each seam ridge or its equivalent is separately formed by turning back the finish material at predetermined spaced intervals to form folds therein, which folds are sewed to the lining fabric one at a time. One form of sewing mechanism which is particularly well adapted for the purpose of sewing seams of the type illustrated in Figures 25 and 26 is illustrated in the remaining figures of the drawing and will now be described in detail. While

obviously a gang or series of sewing heads will be provided corresponding in number to the number of seams to be sewed, only one of such sewing heads will be described in detail herein, as obviously each is a duplicate of the other.

From the drawings it will be noted that each sewing head consists of a pair of twin units A and B, identical with one another and mounted upon a cross head 10 so that the needles thereof reciprocate or move in paths or planes at an angle of substantially 60° to one another, as best seen from Figure 5.

Each of the sewing head units A and B comprises a bearing bracket 11 provided with hub-like extensions 12 and 13 in which are journaled the shafts 14 and 15 of intermeshing spiral pinions 16 and 17. A common drive shaft is provided, one for all of the units A and one for all of the units B of the gang of sewing heads, these drive shafts being indicated by the reference character 18. Each drive shaft 18 is provided, adjacent each of the sewing head units, with a spiral pinion 19 which meshes with the corresponding spiral pinion 16.

As previously pointed out, the sewing head units A and B are arranged so that the needles thereof reciprocate in planes at an angle of substantially 60° to one another, and as a consequence each of these units is arranged at an angle of substantially 30° to its corresponding drive shaft 18. The shafts 18 will be driven in synchronism by any preferred or desired means, preferably also synchronized with the finish and lining fabric feeding means to be referred to.

Each of the sewing head units A and B is removable and adjustably mounted with relation to its corresponding drive shaft 18 so that these units may be removed when desired or may be adjusted longitudinally of the drive shafts to vary and regulate the distance between adjacent sewing heads. This adjustment and removability may be conveniently provided for by employing for each sewing head a pair of brackets 20 adjustably connected to the sewing cross head 10 by means of bolts 21, the heads 22 of which slidably engage in T slots 23 formed in the under side of the head 10. The lower ends of these brackets 20 are provided with opposed inwardly extending sleeves 24 which surround and support the shaft 18 and abuttingly engage on opposite sides of the spiral pinion 19 (see particularly Figure 5).

Each shaft 18 is provided with a longitudinally extending key-way 25 with which a key 26 carried by the spiral pinion 19 engages. This permits longitudinal movement of each pinion 19 with respect to its shaft 18 but prevents relative independent rotation thereof.

The upper end of each bearing bracket 11 is provided with a half bearing recess which not only encloses the lower half of the corresponding pinion 19, but is provided with oppositely extending half sleeve portions 27 which engage the sleeves 24 of the brackets 20. A correspondingly shaped cap 28 pivotally connected as at 29 to the bearing bracket 11 completes the enclosure for the pinion 19 and encloses the top half of the sleeves 24. This cap is removably secured in place by means of clamping screw 30. Obviously by loosening the nuts of bolts 21 the brackets 20 may be adjusted longitudinally of the sewing head cross beam 10 to thus longitudinally adjust the pair of units A and B of each sewing head. By removing the clamping bolts 30 and raising the caps 28 the bearing brackets 11 with the re-

maining structure which is supported thereby may be removed.

Each of the units A and B is rockably adjustable about its drive shaft 18, but independently 5 of each other. For instance, as seen in Figure 1, the unit B is provided with a pair of upstanding lugs or ears 31 which embrace an adjusting screw 32 which in turn is pivotally mounted at 33 at one end thereof to the bracket 20. Lock nuts 34 10 threadedly engage the screw 32 and engage the lugs 31 at one side thereof, whereas an adjustable sleeve nut 35 is threaded upon the screw 32 and engages the lugs 31 at the other side thereof.

The other unit A of the sewing head has provision for permitting adjustable rocking movement if desired. To this end the bracket 20 is formed with a bifurcated lug 36 through which a shank or rod 37 passes, this rod being pivotally connected as at 38 to an extension 39 formed on the cap 28. The rod 37 carries a head 39' against which one end of the spring 40 engages, the other end engaging against an internal shoulder formed on sleeve 41 which surrounds the rod 37. This sleeve is formed with a semi-ball shaped end 42 25 which engages a correspondingly shaped surface on the lugs 36. This construction will permit a rocking movement of the bearing bracket about the shaft 18 in one direction. Movement in the other direction is regulated by an adjustable set screw 43 carried by the lug 36 and engaging extension 39. By grasping the head 44 of the sleeve 41 the sleeve may be moved against the tension of the spring 40 to disengage the sleeve and the shank 37 from the lug 36.

Rotation of each drive shaft 18 rotates the corresponding spiral pinion 19, which through the intermediate spiral pinion 16 rotates spiral pinion 17, keyed to shaft 15. The end of shaft 15 carries an eccentric 45 which is in peripheral engagement with an eccentric link 46. The end of this link 46 is pivoted as at 47 to a slide or sector 48 mounted for oscillatable sliding movement in a guideway 49 fixed to the bearing bracket 11, as for instance by means of screws 50. Thus the eccentric 45 acts through the medium of link 46 to oscillate the sector 48. The shaft 15 extends through an elongated slot 51 in the slide or the sector 48, this elongated slot permitting sliding movement of the sector over the shaft 15.

Also mounted on pivot pin 47 carried by the slide or sector 48 is a needle arm 52. The connection is such that the needle arm 52 pivots or rocks about the pivot pin 47. This rocking movement of the needle arm is caused by means of a link 53 pivotally connected as at 54 to a lateral extension 55 on the needle arm and to a pin 56 carried by the eccentric 45. Thus rotation of the shaft 15 causes a reciprocable movement to be imparted to the sector 48 and a rocking movement to be imparted to the needle arm 52. Each needle arm carries a needle 57.

While the thread may be supplied to the needle in any preferred or desired manner, it will be noted from Figures 3, 4, 10 and 11 that the thread passes through a thread tension 58, thence through a guide 59 and through a thread take-up 60 carried by the end of the needle arm. From the thread take-up 60 the thread passes through an aperture 61 in the needle arm and thence to the needle 57.

The mechanism for presenting the velour or finish fabric and the sheeting or lining fabric to the sewing mechanism is not herein illustrated and described in detail, because it forms a part of our co-pending application filed October 20, 1930,

Serial Number 490,034. However, as previously pointed out, and as diagrammatically illustrated in Fig. 29, the finish fabric F is gathered to provide a plurality of spaced parallel seam ridges and the lining fabric or sheeting L is superposed thereon with portions thereof adjacent to and parallel with the seam ridges S at one side thereof, the cotton bat C being introduced between said fabrics in the tubes formed between said seam ridges as shown in Fig. 2. The finish and lining fabrics are presented to the sewing mechanism in this manner. In Figure 24 the formation conveyor which presents the velour or finish fabric to the mechanism is indicated by the reference character 62, and, as will be noted, comprises an endless chain member carrying suitably shaped formation members 63. Each seam ridge, as it is presented to the sewing mechanism, is stripped from the formation conveyor and is preserved in this condition by means of a sewing plate 64 (see Figure 24) which is mounted to a fixed part of the mechanism 65. The sewing plate is formed with a reduced portion providing a passage 66 through which the needles 57 extend during the sewing operation. By a comparison of Figures 2 and 24 the manner in which the fabrics are presented to the sewing mechanism will be made more apparent. It will be noted that the sewing plates 64 extend into the seam ridges S of the finish fabric F. The lining fabric L is superposed thereon and is arranged with portions thereof parallel with and adjacent to the seam ridges at one side thereof in the manner previously referred to and as illustrated in Figures 2, 25 and 26. The finish and lining fabrics are presented to the sewing mechanism in the condition best illustrated in Figure 2 by the means therein illustrated. It will be noted that the seam ridge S closely embraces the sewing plate 64 and is maintained in this position on the one side by means of a plate member 67 and on the other side by means of a plate member 68. This latter plate member carries a tapered needle guard 69, which maintains free and clear the needle space X referred to in connection with Figures 25 and 26. This needle guard acts as a barrier to prevent the cotton bat C from becoming entangled with the needles. A shouldered plate 70 is arranged adjacent the top edge of the sewing plate 64 at one side thereof and acts to hold the lining L adjacent to and parallel with the seam ridge at one side thereof. The plate 68 is apertured as at 68' and the plate 70 is apertured as at 70' to permit the passage therethrough of the needles.

The construction of the needle arm actuating mechanism is such that each needle has imparted thereto a thrusting and retracting movement and also a rocking movement, the mechanism for operating each needle being so designed, related and timed that the point end of the needle describes a loop. The thrusting and retracting movement of the needle causes it to be thrust through and withdrawn from the fabrics. The rocking movement of each needle insures the spreading of the loop formed by the needle and provides clearance for the other companion needle. In this connection it should be remembered that each sewing head includes a pair of needles working in pairs at an angle of substantially 60° to one another, the working paths of needles intersecting one another immediately beyond the center line of the seam. Moreover, the needle arm actuating mechanism is so constructed and arranged that the needle

rocks about a point coincident with the center line of the seam, so that irrespective of the rocking movement imparted to the needle, each needle pierces the fabrics in the same horizontal plane, and the rocking movement, a greater portion of which is imparted thereto while it is thrust through the cloth, may be accomplished without interference.

The greatest rocking movement is imparted 19 to the point of the needle during the latter part of its thrusting movement and the first part of its retracting movement. In operation the needle is thrust forward through the fabric and during the latter part of this thrusting movement the 15 point of the needle is rocked to its highest position. During the retracting movement, and particularly during the first part of the retracting movement, the needle is rocked so as to lower the point thereof. This combined rocking and 20 retracting movement spreads or opens the loop formed by the needle on its thrusting stroke, and as this loop is opened the other needle, whose path of travel intersects that of the first needle, crosses over the top of the first needle and 25 through the loop formed thereby, so that upon the completion of the retracting movement of the first needle the loop formed thereby is slipped over and carried by the second needle which is just completing its forward stroke. The second 30 needle thereupon rocks to lower its point and spread the loop formed thereby, whereupon the first needle in its second thrusting stroke extends through the loop which it previously made and through the loop which has just been opened or 35 spread by the rocking of the second needle. The resulting stitching is that known as the double chain lock stitch, and the particular manner in which the needles operate to form this stitch will be made more apparent as this description proceeds.

By a comparison of Figures 10 and 11 the manner in which the needle 57 is thrust forward and retracted will be made more apparent. The needle arm 52 partakes of a pivotal swinging 45 movement about the pivot 47, a swinging movement being imparted to the needle arm 52 by means of a link 53 pivoted to the needle arm as at 54 and also pivotally connected to the pin 56 of the eccentric 45. The movement of crank pin 50 56 about the center of shaft 15 of eccentric 45 moves the needle from the position illustrated in Figure 10, which is its extreme retracted position, to the position illustrated in Figure 11, which is the end of its forward or thrusting movement.

During this movement of the needle arm the eccentric 45 acting through the eccentric link 46 causes the sector or slide 48 to slidingly reciprocate in guideway 49. The pivot 47 for the needle arm 52 is carried by this sliding sector 48 so that as a consequence the point of the needle will describe a loop-like path. The sector 48 and the guideway 49 have arcuate curved engaging surfaces struck from the center H, which is the center line of the seam. Thus, while the needle partakes of both a reciprocating and rocking movement, it will always pass through the point H and all rocking movement will be about this point H, so that the engagement of the needle 65 with the fabrics will in no wise interfere with these movements imparted thereto. As will be apparent, the rocking of the needle is the direct result of the reciprocal movement of the slide 48 which alters the horizontal plane of the pivot 47. In Figure 9 the point of the needle is shown

in approximately the position it assumes prior to being rocked or lowered; and in Figure 8 the point of the needle is shown approximately in the position it assumes after being rocked downwardly and at the beginning of its retracting 5 movement.

By reference to Figure 27 the action of the slide 48 on the needle arm 52 and needle 57 will be more apparent. In this figure the position the needle arm assumes when the slide 48 is at its extreme left hand position is illustrated by heavy black lines and the position the needle arm and needle assume when the slide 48 is at its extreme right hand position is illustrated by light lines. The movement of the fulcrum of the needle arm 10 from the light line position to the heavy line position lowers the horizontal plane of this fulcrum point and thus rocks the needle arm in the manner and to the extent indicated, this rocking movement taking place about the center H 15 which is the center about which the arcuate bearing surfaces of the slide 48 and guide 49 are struck. As previously mentioned, this reciprocating movement of the slide 48 occurs by reason of the action of the eccentric link 46 actuated 20 by cam disk 45, and inasmuch as the needle arm operating crank pin 56 is also carried by this eccentric disk 45 and is simultaneously partaking of movement about the center of the shaft 15 (which carries the eccentric disk 45) the needle 25 is simultaneously partaking of its thrusting and retracting movement. Thus there are also indicated in this figure the extreme positions of the needle 57, the extreme thrusting position being indicated by the dot and dash lines and the extreme retracted position by the dotted lines.

By reference to Figure 28 the movement of the point of the needle 57 and consequently the manner in which the needle reciprocates and rocks will be made more apparent. In this figure 40 the center line of the shaft 15 of the eccentric disc 45 is indicated, and about this center is described the path of movement of the crank pin 56, which, through the medium of link 53 oscillates the needle arm 52 and consequently the 45 needle 57. The path of travel of the crank pin 56 has been divided into eighteen increments and numbered accordingly, starting at 1 with the crank pin above and in vertical alignment with the shaft 15. The path of the point of the 50 needle 57 has also been indicated, and the positions of the needle point indicated on this path, the numbers corresponding to the positions of the crank pin 56. It will be noted from this diagram that the point of the needle describes a 55 substantially "figure eight" path, but that the needle passes through the center line of the seam H heretofore referred to. It will be further noted from this diagram that the greatest movement with respect to the alteration of the horizontal plane of the point of the needle occurs during the end of the thrusting movement of the needle and the beginning of its retracting movement. In the example given the shaft 15 is presumed to rotate in the direction of the arrow 60 and the point of the needle to travel in the direction indicated by the sequence of the numbers applied to its path of travel.

As illustrated, the needles 57, while extending generally transversely to the longitudinal path 70 of travel of the seam, are each inclined with respect to a vertical plane which transversely intersects this path of travel of the seam, one of the needles being inclined in the direction of travel of the seam and the other needle being op- 75

positely inclined with its point extending opposite to the line of travel of the seam. Thus, while the needle to the left, as viewed for instance in Figure 12, is in the work, the work slides downwardly toward the point of the needle and while the needle to the right is in the work, the work slides up further onto the needle. The openings 68' and 70' in the plates 68 and 70, respectively, permit this slight sliding movement of the work.

5 10 15 20 25 30 35 40 45 50 55 60 65 70 75

In this manner the work is permitted to travel despite the substantially continuous engagement of the needles with the seam.

The sewing operation will be best understood by reference to Figures 12 to 21 inclusive, where- 15 20 25 30 35 40 45 50 55 60 65 70 75

in the thread carried by the right hand needle is indicated by a black line and the thread carried by the left hand needle is indicated by spaced light lines.

As seen from Figure 12, the right hand needle is just completing its forward stroke and has pulled the thread through the fabric. As this needle starts to retract to form a loop in this thread, it is also rocked downwardly to open or spread the loop as indicated in Figure 13. Simultaneously the left hand needle is partaking of its thrusting movement, and as its path of travel intersects that of the right hand needle, it passes over the right hand needle, which, as previously mentioned, has been lowered to thus clear the path for the left hand needle. The left hand needle in passing over the right hand needle is thrust through the loop of the right hand needle. In Figure 14 the left hand needle is shown at about the end of its thrusting movement and the right hand needle is completely retracted and the loop formed thereby is slipped well on to the left hand needle. In Figure 15 the left hand needle is beginning its retracting movement and is being lowered and the loop carried thereby is being spread. The right hand needle is commencing its thrusting movement. In Figure 16 the left hand needle is still retracting and the right hand needle has pierced the fabric and is being thrust through the loop previously formed thereby and also through the spread loop of the left hand needle. In Figure 17 the left hand needle is shown completely retracted and the right hand needle substantially at the end of its thrusting movement. In this figure the first and second loops are still engaged by the right hand needle. In Figure 18 the left hand needle is entering the loop being spread by the retraction of the right hand needle, and in Figure 19 the right hand needle is well on its retracting movement and the left hand needle is near the end of its thrusting movement. In Figure 20 the left hand needle is approximately at the end of its thrusting movement and the right hand needle has been completely retracted and disengaged from the first two loops formed. In Figure 21 the right hand needle is again commencing its thrusting movement, while the left hand needle is retracting. This movement of the needles is repeated, and as a consequence a double chain lock stitch, such as is illustrated in Figure 22, is created. The manner in which the stitching appears on the reverse side of the fabric is illustrated in Figure 23.

From the foregoing, it is believed that the manner of execution of my improved method and modus operandi of the illustrated mechanism will be apparent to those skilled in this art. With the herein described method it is possible to unite the finish and lining fabrics in such a manner that the seams will be practically invisible on the face of the completed article, and the lining or

backing may be stretched taut in the subsequent application of the upholstery to seats and the like, without strain or other injury to the stitching. This method consists broadly in stitching from the outside of a tubular or plaited fabric through a single thickness of lining material and completing the stitch in the interior of the tube or plait. The mechanism herein described contemplates automatic means for presenting the finish and lining materials, with or without cotton bat associated therewith, to the sewing mechanism and automatic means for uniting these fabrics by stitching extending from the outside into the interior of the tubes of the upholstery where it is completed.

15 20 25 30 35 40 45 50 55 60 65 70 75

Obviously changes and modifications may suggest themselves to those skilled in this art, and to this end reservation is made to make such changes in any of the non-essential details as may come within the purview of the accompanying claims.

We claim as our invention:

1. Sewing mechanism comprising a pair of needles working in planes at an angle to one another from the same side of the seam, each needle having a thrusting and retracting movement, and a 25 rocking movement prior to the thrusting movement of the other needle.

2. Sewing mechanism comprising a pair of needles working in paths which angularly intersect one another but from the same side of the seam, 30 said needles respectively partaking simultaneously of thrusting and retracting movement, each needle having a rocking movement at the end of its thrusting movement.

3. Sewing mechanism comprising a pair of needles working in paths which angularly intersect one another, said needles working from the same side of the seam and each needle having a thrusting and retracting movement, and a 40 rocking movement prior to the intersection of its working path by the other needle.

4. Sewing mechanism comprising a pair of needles working in paths which angularly intersect one another, said needles working from the same side of the seam and each needle having a 45 thrusting and retracting movement, and a rocking movement substantially at the ends of its thrusting and retracting movements.

5. Sewing mechanism comprising a pair of needles working in vertical planes which intersect one another, each needle having a thrusting and retracting movement, and a 50 rocking movement to lower its point end substantially prior to the commencement of its retracting movement.

6. The combination with means for feeding 55 plies of finish and lining fabric and forming seam ridges in one fabric and arranging the other fabric parallel to the seam ridges at one side thereof, of means for uniting the fabrics comprising needles extending through the parallel 60 and seam ridge portions of the fabrics into the space therebetween and means for operating said needles to complete the stitches within the space between said fabrics.

7. The combination with means for feeding 65 plies of finish and lining fabric and forming seam ridges in one fabric and arranging the other fabric parallel to the seam ridges at one side thereof, of sewing mechanism for uniting the fabrics comprising needles working in angularly 70 intersecting paths, means for imparting a thrusting and retracting movement to each needle to thrust the same through the parallel and seam ridge portions of the fabrics into the space therebetween, together with means for further op- 75

- erating said needles to complete the stitches within the space between said fabrics.
8. The combination with means for presenting finish and lining fabrics to a sewing mechanism whereby to provide parallel tubes in the united fabrics, of a sewing mechanism comprising a pair of needles working in paths which intersect one another, means for imparting thrusting and retracting movements to the needles to unite the fabrics by stitching extending from the exterior of said tubes to the interior thereof and means for further actuating said needles to complete the stitches within said tubes.
9. The combination with means for gathering a finish fabric to form spaced seam ridges and arranging a lining fabric with portions thereof parallel to the seam ridges to form tubes therebetween, of sewing mechanism comprising a pair of needles, means for thrusting and retracting said needles through the parallel and seam ridge portions of said fabrics on paths which intersect one another within said tubes and means for actuating said needles to complete the stitches within said tubes.
10. A sewing mechanism comprising a pair of needles, means for simultaneously imparting thrusting and retracting movements respectively to said needles, said needles moving in vertical planes which intersect one another, and means for rocking each needle at a predetermined point in its travel to lower its point to spread the loop formed thereby to permit the engagement thereof by the other needle.
11. A sewing mechanism comprising a pair of needles, means for imparting thrusting and retracting movements to each needle, said needles moving in opposite directions and working in planes which intersect each other at an acute angle, and means for rocking each needle at a predetermined point in its travel to lower its point to cause a spreading of the loop formed thereby to permit the engagement of the loop by the other needle.
12. A sewing mechanism comprising a needle arm, a needle carried thereby, a slidable sector, a pivot for the needle arm on said sector and means for oscillating said needle arm and sector.
13. A sewing mechanism comprising a needle arm, a slidable sector, a pivot for the needle arm on said sector and means for oscillating said needle arm and for oscillating said sector to vary the pivot of said needle arm.
14. A sewing mechanism comprising a needle arm, a slidable sector, means for pivotally mounting said needle arm on said sector and means for oscillating said needle arm and sector in timed relation.
15. A sewing mechanism comprising a needle arm, a slidable member, a pivot for the needle arm on said slidable member, an eccentric disc for oscillating said slidable member and a crank pin and link connection between said disc and said needle arm for oscillating said needle arm about its pivot.
16. Sewing mechanism including a needle and needle arm, a pivot for said needle arm with means for oscillating said arm about said pivot to thrust the needle through the seam at a point coincident with the center line thereof and means for moving said pivot on an arc having said point as its center.
17. A method of forming upholstery which comprises feeding two sheets of fabric into superimposed relationship, bringing said sheets into engagement along spaced portions to form simul-
- taneously a series of parallel tubes therebetween, and thereafter forming lines of stitching passing through the engaged portions of the sheets into the interior of the tubes and completed within the latter.
18. In an upholstery machine, means for feeding two sheets of material longitudinally in superposed relation, means for gathering one of said sheets transversely and forming a plurality of parallel, longitudinal, upstanding seam ridges with a fullness therebetween while said sheet is fed longitudinally, and means for uniting said sheets by a plurality of parallel lines of stitching passing through both layers of said seam ridges and through one thickness only of the other sheet.
19. In an upholstery machine, means for feeding fabrics and forming seam-portions and intervening pleat-fullnesses, the seam-portions of one fabric being of U-form, and sewing mechanisms adapted to unite the seam-portions, each sewing mechanism comprising a reciprocating needle working through one thickness solely of one fabric at its seam-portion and through two thicknesses of the other fabric at its seam-portion, and means coacting with said needle in the space between the superposed fabrics to complete the stitches therein.
20. In a machine of the character set forth, means for feeding fabrics and forming seam-portions and intervening pleat-fullnesses, the seam-portions of one fabric being of U-form, sewing mechanisms adapted to unite said seam-portions, each sewing mechanism comprising a reciprocating needle working through more thicknesses of one fabric than of the other, said needle working through the U-form seam-portion, and means coacting with said needle within the space between the superposed fabrics to complete the stitches therein.
21. In a machine of the character set forth, means for feeding fabrics and forming seam-portions and intervening pleat-fullnesses, the seam portions of one fabric being of U-form, sewing mechanisms for uniting the seam-portions, each sewing mechanism comprising a transversely reciprocating needle working through a U-form seam-portion in one fabric and a single thickness of the other fabric, and means coacting with said needle within the space between the superposed fabrics to complete the stitches therein.
22. In a machine of the character set forth, means for feeding fabrics and forming seam-portions and intervening pleat-fullnesses, the seam-portions of one fabric being of U-form, sewing mechanisms for uniting said seam-portions, each sewing mechanism comprising a needle working through said fabrics, said needle being mounted to reciprocate in a plane extending transversely of said U-form seam-portions, housing members disposed between the superposed fabrics and over which one of said fabrics is advanced, and means coacting with said needles within said housing members to complete the stitches therein.
23. In a machine of the character set forth, means for advancing a cover fabric, means for advancing a lining fabric, means for feeding batts between said fabrics, and a plurality of sewing mechanisms for sewing spaced seams in said fabrics extending longitudinally thereof, each sewing mechanism comprising a needle working through both fabrics, means forming a working space between one of said fabrics and a batt, and means cooperating with said needle within said

working space for completing the stitches therein.

24. In the manufacture of pleated upholstery, the steps which comprise, feeding fabrics and batts with the batts disposed between the fabrics, forming seam-portions in the fabrics, holding each batt spaced from one side of a seam-portion to provide interior sewing spaces, and engaging loops of one thread with loops of a second thread formed in said sewing spaces.

10 25. In the manufacture of pleated upholstery, the steps which comprise, feeding fabrics and batting with the batting disposed between the fabrics, forming a plurality of longitudinally extending seam-portions, holding the batting spaced from one side of the seam-portion to provide interior sewing spaces, forming loops of one thread and engaging said loops with loops of a second thread formed in said sewing spaces.

15 26. In the manufacture of pleated upholstery, the steps which comprise, feeding fabrics and

batts with the batts disposed between the fabrics, forming seam-portions in the fabrics, holding each batt spaced from one side of a seam-portion to provide interior sewing spaces, and simultaneously sewing the fabrics to each other between the batts by passing one thread through the fabrics, forming loops of said thread and engaging said loops with loops of a second thread formed in said sewing spaces.

27. In the manufacture of pleated upholstery, the steps which comprise, advancing a lining fabric and a main fabric with batts disposed therebetween, forming seam-ridges between the batts, then uniting said fabrics by stitches of a thread passed therethrough from the outer side of one of them and engaging loops formed in said thread by loops of a second thread formed between the fabrics.
